UNITED STATES PATENT OFFICE.

GEORGE WASHINGTON LANCASTER, OF RICHMOND, VIRGINIA.

TELEPHONE CABINET OR HOOD.

1,014,492.

Specification of Letters Patent.

Patented Jan. 9, 1912.

Application filed December 7, 1910. Serial No. 596,145.

To all whom it may concern:

Be it known that I, GEORGE WASHINGTON LANCASTER, a citizen of the United States, residing at Richmond, in the county of 5 Henrico and State of Virginia, have invented certain new and useful Improvements in Telephone Cabinets or Hoods; and I do hereby declare the following to be a full, clear, and exact description of the invention, such as will enable others skilled in the art to which it appertains to make and use the same.

This invention relates to improvements in hoods or cabinets for telephones, and is 15 so constructed as to inclose the head and preferably the upper part of the speaker's person so as to prevent noises from the outside of the hood from disturbing the speaker.

The object in view is the arrangement of 20 an improved cabinet or hood adapted to have arranged therein both the telephone transmitter and receiver, the construction being such that the head and upper part of the speaker's person will be inclosed in the hood 25 in order that a conversation may be carried on privately and without noise or disturbance.

A further object in view is the arrangement of improved means for preventing the 30 transmission of sound from the cabinet around the speaker's person.

A still further object of the invention is the arrangement of improved means for permitting the operation of the telephone switch 35 or hook from the outside of the cabinet, together with improved means for permitting a person to see through the cabinet at certain points for taking down data as desired.

With these and other objects in view the 40 invention comprises certain novel constructions, combinations, and arrangement of parts as will be hereinafter more fully described and claimed.

In the accompanying drawings: Figure 45 1 is a perspective view of an embodiment of the invention, certain parts being broken away to better illustrate the invention. Fig. 2 is an elevation of the construction shown 50 in Fig. 1. Fig. 3 is a section through Fig. 1 on line 3—3. Fig. 4 is a front view of the telephone, the same being shown in connection with a fragment of the hood. Fig. 5 is a rear view of the telephone shown in 55 Fig. 4.

In forming a device embodying the invention an improved hood is provided designed to co-act with an improved and specially made telephone instrument. The hood is formed of any desired material, and is arranged, preferably with a number of windows so that the occupant may have a view of the surroundings, including the table on which the hood is placed or to which the hood is secured, so that data of any kind 60 may be noted on tablets or the like arranged on the table. The hood is formed with an opening which freely admits the head and part of the body of the speaker's person, but is arranged with padding or sound deadening cushions for preventing sound to be transmitted from or into the hood around the speaker's person. The telephone apparatus is arranged so that the receiver is held 65 against or near the ears of the speaker, while the mouth piece of the transmitter is at the proper distance from the mouth of the speaker. These arrangements are associated with means operable by the speaker from the outside of the cabinet for raising and 70 lowering the ordinary hook of the telephone instrument for switching on and off the instrument as desired.

In order that the invention may be more clearly understood an embodiment of the 85 same is shown in the accompanying drawings, in which 1 indicates a table which is preferably rotatably mounted on a stem or support 2. The stem or support 2 has a base 3 of any desired kind for properly holding the stem 2 and cabinet 4 carried by the table in proper position for use. The stem 2 may be made of such a height as to allow the use of the cabinet by a person standing 90 or sitting down according to which is preferable.

The cabinet 4 is formed with a housing of any desired material, as for instance wood, or metal, and is provided with a plurality of windows 5 some of which are so arranged that the person using the hood may easily see a tablet or other article on the table 1 and make use of the same if desired.

The cabinet 4 may be made of any desired 105 shape, but is provided with a notched out portion at point 6, and with an opening 7 through which the head and part of the shoulders of the person is passed when using the device.

The hood 4 is preferably bulged at 8 for causing opening 7 to more nearly conform to the shape of the shoulders of a person.

A pad or cushion 9 may be provided if 5 desired to contact with the body of the person using the hood, and to assist in preventing sound from entering or escaping from the hood around the person.

Arranged in the hood 4 is a floor member 10 or partition 10 on which the telephone stand 11 is placed. The usual mouth-piece 12 is provided, but instead of the usual receiving apparatus there are provided ear members 13—13 held in place by spring 14 which normally presses the ear members against the head of the person using the device. A suitable bracket 15 is provided for supporting the spring 14 on stand 11. If desired the spring 14 may be pivotally mounted so 20 as to permit more or less movement of the head of the person as desired.

Pivotally mounted on stand 11 is a bell crank lever 16 formed with a projection or arm 17 designed to depress the ordinary hook 25 or switch arm 18 of the telephone instrument. A controlling bar 19 is pivotally mounted at 20 to lever 16, and is arranged to extend through one of the walls of the hood 4, so as to be moved by the hand of 30 the operator, which, of course remains on the outside of the hood. A notch 21 is provided in bar 19 arranged to engage one of the walls of the hood 4 or a stop of any desired kind for holding the bar against movement 35 unless positively operated. Ordinarily the notch 21 is in engagement with its retaining bar so as to hold the hook 18 depressed. When any one desires to use the telephone the bar 19 is simply raised so that notch 21 40 will be disengaged and the ordinary spring action of hook 18 will cause the same to rise in the usual manner and move bar 19 longitudinally. When the person using the telephone desires to shut off the instrument, bar 19 is pulled longitudinally, which will 45 depress hook 18 and then notch 21 is caused to engage its retaining member.

What I claim is:

1. In a device of the character described, 50 a hood formed with a substantially rectangular housing, and a rounded bulged portion on one side, said housing being formed with a neck opening, part of said opening

being beneath said bulged portion, where-
by the opening approaches the correct shape 55
for accommodating the person of the
speaker, means for supporting a telephone
instrument in the hood, and means for
switching on and off the telephone instru-
ment by the speaker from the outside of the 60
hood.

2. In a device of the character described, 65
a hood formed with an opening for the ad-
mission of part of the speaker's person, a
telephone instrument formed with a trans-
mitter and a pair of receivers, means for
holding the receivers against the ears of the
speaker, and means operable from the out-
side of the hood for switching on and off
the telephone instrument. 70

3. In a device of the character described,
a telephone hood, means for supporting a
telephone therein, a bell crank lever con-
nected with the telephone formed with an
arm for engaging the hook of the telephone,
75 and a reciprocating controlling bar con-
nected with said bell crank lever for con-
trolling the action thereof.

4. In a device of the character described,
a hood, a support for supporting a tele- 80
phone instrument in the hood, a hook oper-
ating member pivotally connected with the
telephone instrument, a reciprocating bar
pivotally connected with the member for
controlling the hook of the telephone instru- 85
ment, said bar being formed with a notch,
and means associated with the hood for en-
gaging said notch for locking the bar nor-
mally against longitudinal movement.

5. In a device of the character described, 90
a hood formed with a neck opening, means
for supporting a telephone in said hood, a
bar connected with said telephone for oper-
ating the same, said bar extending to the
exterior of said hood and formed with a 95
notch and pivotally mounted catch arranged
on said hood adapted to engage said bar in
said notch for locking the bar normally
against movement.

In testimony whereof I affix my signature 100
in presence of two witnesses.

GEORGE WASHINGTON LANCASTER.
